Fig. 2.

UNITED STATES PATENT OFFICE.

WILLIAM H. SCHOONMAKER, OF MONTCLAIR, NEW JERSEY.

METHOD OF HEATING.

Original application filed March 3, 1917, Serial No. 152,198. Divided and this application filed October 5, 1921. Serial No. 505,491.

To all whom it may concern:

Be it known that I, WILLIAM H. SCHOONMAKER, a citizen of the United States, residing at Montclair, in the county of Essex and State of New Jersey, have invented certain new and useful Improvements in Methods of Heating, of which the following is a specification.

This application is a division of my application Serial Number 152,198, filed March 3, 1917, and has particular reference to the method of hastening the heating action of the apparatus disclosed therein.

The present invention deals with a method by which the heating efficiency of an apparatus for house heating is increased, and is applicable to ordinary steam heating systems, either to the so-called "one pipe" or to the so-called "two pipe" systems, also to the modification of steam heating systems known as the vapor heating system.

As a method the invention involves the application of suction or partial vacuum to the heating coils or radiators of the system, upon the adjustment of the boiler damper or dampers to cause increased combustion or upon the decrease of temperature or of the partial vacuum in the return line below a predetermined value, and the shutting off of such suction or partial vacuum upon the adjustment of such boiler dampers to cause decreased combustion, or upon the rise of temperature or partial vacuum to above a certain degree. My invention further comprises a method whereby the action of the suction apparatus is stopped upon establishment of a predetermined degree of partial vacuum in the heating system, and is started again upon fall of that partial vacuum below a predetermined degree; and my invention further comprises means whereby upon the establishment of a predetermined temperature in the return or air-withdrawal line of the system the operation of such suction apparatus is stopped, and is started again upon the fall to a predetermined degree of the temperature in said return or air-withdrawal line. By so applying suction to, or creating a partial vacuum in, the said return or air-withdrawal line, the temperature at which the water in the boiler evaporates is greatly lowered, and thereby the time required to fill the heating coils or

radiators with steam is greatly reduced. My invention further comprises means whereby in the event of water being drawn up by suction into the return line of the heating system to some predetermined point, a connection will be opened automatically between the supply line and return line, balancing pressures, and causing the water drawn up to return to the boiler.

The objects of my invention are, to render steam heating systems and vapor heating systems more quickly responsive; to cause the heating coils of the radiator or radiators of the system to be filled with steam more quickly, upon the adjustment of the furnace damper or dampers for increased combustion, more particularly when the boiler has not been supplying steam to the heating coils for a considerable length of time (as for example during the night when the boiler has been shut off, i. e., the drafts have been set so that the boiler has not generated steam); to obtain increased fuel economy; and generally to accomplish the above objects while retaining simplicity of apparatus and without material addition to expense of apparatus.

Heretofore so-called "vapor heating systems" have been employed, wherein once steam has been generated in the boiler and heating system, at or above atmospheric pressure, a partial vacuum is maintained, for a considerable time at least, in the heating coils or radiators, and in the boiler; but these systems, so far as I am aware, have commonly required that steam shall first be generated at or above atmospheric pressure, or else have required that a suction pump shall be started by hand or by means other than the normal automatic control apparatus of the boiler itself. Such apparatus does not provide for the automatic establishment of a partial vacuum in the heating system at the time when that partial vacuum is most needed, i. e., when the drafts of the boiler are opened, automatically or otherwise, in the morning, after the furnace has been shut off all night. It is obvious that if, at or about the time when the drafts of the furnace are opened in the morning, a partial vacuum be applied to the heating coils or radiators of the system, steam will be generated in the boiler much sooner than other-

wise, and the heating coils or radiators will be filled with steam much sooner than otherwise. This is accomplished by the method and means hereinafter described.

5 I will now proceed to describe my invention with reference to the accompanying drawings, illustrating one embodiment of an apparatus employed in carrying out the present method, and will then point out the 10 novel features in the appended claims. In the drawings:

Figure 1 shows, more or less diagrammatically, an elevation of a heating system embodying my invention, installed in a house, 15 the walls and floors of which house are shown in section; Figure 2 shows a central vertical section of an automatic air valve forming a portion of my heating system; Figure 3 shows a central vertical section of 20 a diaphragm-operated valve forming a portion of the control mechanism of an exhauster employed in my said system; Figure 4 is a view, similar to Figure 1, showing the application of my invention to a so-called 25 "single pipe" heating system; Figure 5 shows, more or less diagrammatically, an elevation of the said automatic air valve, together with means operated by that air valve for operating a control valve of the 30 said exhauster, such control valve being shown in vertical section; Figure 6 shows a fragmentary vertical section of a float-operated valve employed in my system; and 35 Figure 7 shows a central vertical section of a check valve which may be employed in the single pipe system shown in Figure 4.

Numeral 1 designates an ordinary heating boiler; 2 a steam supply pipe extending therefrom to the radiators or heating coils 40 3; and 4 designates the return line from the radiators to the boiler. 5 designates the ordinary draft damper of the boiler and 6 the ordinary "check" damper in the connection to the smoke pipe 7, these dampers being arranged to be operated automatically by the usual regulating lever 8 itself operated by the usual diaphragm 9, the dampers 5 and 6 being connected to lever 8 by the usual flexible connection 10 and 11.

50 12 designates a valve casing shown in detail in Figure 2.

13 designates a suction producing apparatus, the particular type of apparatus shown being a water-jet exhauster, of well known construction; though the particular construction of suction apparatus employed is immaterial, in a broad sense. I have shown this suction producing device as provided, in its water supply line, with a valve 14 connected to the regulating lever 8 of the boiler by a connection 15, in such manner that as the damper 5 is opened and the damper 6 closed, the valve 14 will be opened, so starting the suction producing device 13 in 65 operation; and as said damper 5 is closed

and damper 6 opened, valve 14 will be closed, so stopping the action of the suction producing device 13.

In the water supply line to the exhausting apparatus 13 there is also another valve 16 (see Figure 3) illustrated as of the dia- 70 phragm-operated type, and arranged to close when a predetermined degree of suction or vacuum has been reached in the heating system, and to open when that suction or degree of vacuum decreases considerably; 75 the opening and closing of this valve controlling the action of the exhausting apparatus 13.

Referring now to Figure 2: Within the valve casing 12 there is a thermo-expansible member 17 provided with an adjustable anchoring device 18 at its left hand end. This member 17 is connected by a pivoted lever 19 to a link 20 having a slip-connection with another link 21 itself connected to a check valve 22. Valve casing 12 is interposed in the steam return line 4; and beyond the check valve 22 said valve casing 12 is connected by a pipe 23 to the exhauster 13. Furthermore, link 20 is connected to link 21 by a spring-slip-connection 24, which serves to prevent destruction of check valve 22 after valve 22 has seated, in case member 17 expands still further, and serves to permit the valve 22 to remain closed upon contraction of member 17. The construction is such that, when there is steam in return pipe 4, such steam will fill the valve casing 12, the varying temperatures of such steam causing 80 varying expansion of the member 17, which expansion is communicated, through lever 19 and links 20 and 21, to valve 22. Should return line 4 be cold, valve 22 will be open. When the steam in the return line reaches 85 some predetermined temperature, the corresponding expansion of member 17 will close check valve 22. The valve casing 12 serves, 90 it will be seen, as a suction-connection between the exhauster 13 and the return line 4. 95

It may be understood that the regulating lever 8 of the furnace is arranged to be operated by any of the well known devices, (for example, a so-called time-controlled thermostat 25 electrically controlling a 100 damper-operating motor 26) for holding the air draft 5 of the furnace closed and the check valve 6 of the furnace open, during the night, and for opening the air damper 5, and closing the check damper 6, in the 105 morning. Such opening of the air damper and closing of the check damper will be accompanied by a downward motion of the right hand end of lever 8 which will open the valve 14, starting operation of the ex- 110 hauster 13 and producing a partial vacuum in the heating system, which will insure the filling of that system with steam long 115 before boiling point at atmospheric pressure has been reached in the boiler. When 120

the temperature in the return line 4 has reached some predetermined value, the expansion of member 17 will close valve 22; and almost immediately thereafter valve 16 5 will close, shutting off the exhauster 13; for with valve 22 closed the partial vacuum beyond such valve will quickly reach the value at which the diaphragm actuating device of valve 16 is set to close that valve. 10 Preferably, within the valve casing 12 a shield 27, covering the expansible member 17, is provided to prevent direct impact of steam or hot water formed by condensation of the steam upon the member 15 17. It is intended that this member shall act by expansion due to heat of steam diffused through the valve casing 12, rather than by heat due to impact of steam or hot water directly on member 17. Check valve 20 22 will close if not already closed when some predetermined sufficient degree of partial vacuum has been reached in return pipe 4, whether or not the member 17 has expanded to an extent sufficient to close valve 25 22; the slip connection 24 permitting the closing of said valve 22 by partial vacuum derived from pipe 4.

It will be seen that, in the event of lowering of temperature of the fluid returned 30 through pipe 4, below a predetermined degree, expansible member 17 will open valve 22. It will be seen that by this apparatus the radiators 3 are maintained under some suction throughout the day, unless the temperature of the return steam or water becomes so high as to close valve 22, in which event there is no need for partial vacuum in the radiators.

While valve 16, operated by suction, provides a means whereby the operation of the exhauster 13 will be stopped when valve 22 is closed, either by expansion of member 17, or by establishment of a predetermined degree of suction in the return line 4, still 45 it is desirable that means be provided for the stopping of the operation of the exhauster 13 as a result of expansion of member 17 to some predetermined degree, independent of the closing of valve 22, and 50 operation of valve 16. Therefore I have provided mechanical means whereby expansion of member 17 causes the stoppage of the operation of the exhauster. In this way unnecessary intermittent starting and stopping of the operation of the exhauster 13, by valve 16, due to variation of partial vacuum behind the valve 22 when that valve 55 is closed, is avoided.

This mechanical means for controlling 60 the operation of the exhauster 13 by expansible member 17, is shown particularly in Figure 5. In the water supply line 28 leading to the exhauster there is a valve casing within which is arranged a valve 29 adapted 65 to be opened and closed by the raising

and lowering of its stem 30. On the pivot shaft 31 of lever 19 (Figure 2) there is an arm 33 having at its end a slot in which works a pin carried by a pivoted arm 34; the other end of this arm 34 working between stops 35 and 36 of valve stem 30. A compression spring 37 is arranged to tend to hold arm 33 either in the position shown or in a reverse position, i. e., said spring tends to hold valve 29 either wide open or 70 fully closed. It will be apparent that when member 17, within the valve casing 12, expands sufficiently, arm 33 will have raised arm 34 sufficiently to cause spring 37 to close valve 29 quickly; so stopping the operation of the exhauster 13, and holding that exhauster against operation until, by contraction of member 17, the position of arm 34 is reversed to the position shown in Figure 4; whereupon that exhauster may begin operation again, provided both valves 14 and 16 be then opened; and valve 16 will be open, when member 17 is so contracted, unless there be in return line 4 such a predetermined degree of suction that the operation of the exhauster is not required.

Whether valve 14 will be opened or not when valve 29 is so opened, will depend upon the position of the damper 5. If damper 5 be closed (for example it may be held closed at the time by the action of the thermostat motor 26) then valve 14 will not be open and exhauster 13 will not operate.

In some conditions it might happen that, through the occurrence of a partial vacuum in the return line 4, water might be drawn up into that return line, to a point considerably above the water level in the boiler; and this might lead to very undesirable conditions. To obviate this, I provide, in the return line 4, a float chamber 38, located above the normal water level of the boiler, but below the valve casing 12; and within this float chamber there is a float 39 connected by a rod 40 to a valve 41 having a port 42 adapted, when the float is raised, to place in communication with each other pipe lines 43 and 44 leading respectively to the return line 4 (at a point well above the valve casing 12) and to the supply line 2. It will be seen that water rising in return line 4 to an extent sufficient to partly fill float chamber 38 and to raise the float therein, will result in the connection of pipes 43 and 44, with consequent balancing 110 of pressures (in this case negative pressures) in the two sides 2 and 4 of the heating system; whereupon the water which has risen in the return line 4 will drop again 115 to normal water level.

As illustrated in Figure 4 in the case of a one pipe system, a return pipe 4' may be connected to the ordinary air valves 30' of the radiators 3 and may lead to the valve casing 12, which in that event serves 120 125 130

as a supplemental air valve for the entire system, besides serving to regulate the application of vacuum to the radiators and besides serving as means, in connection with the pipe 4', for returning any drip from the air valves to the boiler.

In speaking of partial vacuums, or pressures below atmospheric, it is common to speak of the partial vacuum being increased when the absolute pressure is lowered, and to speak of the partial vacuum as having decreased when the absolute pressure has risen. It is in this sense that I have mentioned increase and decrease of suction or partial vacuum in the above description.

What I claim is:

1. The herein described method of hastening the heating action of steam heating systems having a distributing conduit and a boiler for supplying steam thereto, said boiler having a damper regulating the action thereof, which comprises automatically applying suction to the distributing conduit and through the conduit to the boiler, upon change of adjustment of the damper of the boiler in a sense to cause increase of the heating action of the boiler.

2. The herein described method of regulating the heating action of a steam heating system having a distributing conduit and a boiler for supplying steam thereto, said boiler having a regulating damper, which comprises automatically applying suction to the distributing conduit upon change of adjustment of said damper of the boiler in a sense to cause increase of the heating action of the boiler, and automatically ceasing the application of such suction upon change of adjustment of said boiler damper in a sense to cause reduction of the heating action of the boiler.

3. The herein described method of regulating the heating action of a steam heating system having a distributing conduit and a boiler for supplying steam thereto, said boiler having a regulating damper, which comprises automatically applying suction to the distributing conduit upon change of adjustment of said damper of the boiler in a sense to cause increase of the heating action of the boiler, and automatically ceasing the application of such suction upon establishment of a predetermined degree of partial vacuum in the distributing conduit.

4. The herein described method of regulating the heating action of a steam heating system having a distributing conduit and a

boiler for supplying steam thereto and itself having a regulating damper, which comprises applying suction to such distributing conduit upon change of adjustment of said damper of the boiler in a sense to cause increase of the heating action of the boiler, and ceasing the application of such suction upon establishment of a predetermined temperature in the suction end of said distributing conduit.

5. The herein described method of hastening the heating action of steam heating systems having a distributing conduit and a boiler for supplying steam thereto, said boiler having a damper regulating the action thereof, which consists in automatically producing a reduction in pressure in the distributing system simultaneously with the opening of the combustion draft damper of the boiler.

6. The herein described method of hastening the heating action of steam heating systems having a distributing conduit and a boiler for supplying steam thereto, said boiler having a damper regulating the action thereof, which consists in automatically applying suction to a portion of the distributing conduit to promote circulation therethrough simultaneously with the opening of the boiler damper.

7. The herein described method of hastening the heating action of steam heating systems having a distributing conduit and a boiler for supplying steam thereto, said boiler having a damper regulating the action thereof, which consists in automatically producing a reduction in pressure in the distributing conduit simultaneously with the opening of the damper of the boiler.

8. The herein described method of hastening the heating action of steam heating systems which consists in automatically producing a reduction in pressure in the distributing conduit simultaneously with an increase in the heating action within the boiler.

9. The herein described method of hastening the heating action of steam heating systems which consists in automatically producing a reduction in pressure in the distributing conduit simultaneously with an increase in the heating action within the boiler, and ceasing the reduction in pressure upon establishment of a predetermined temperature in the distributing conduit.

In testimony whereof I affix my signature.

WILLIAM H. SCHOOONMAKER.
